US0D1039159S

(12) **United States Design Patent** (10) **Patent No.:** **US D1,039,159 S**
(45) **Date of Patent:** **** Aug. 13, 2024**

(54) **MEDICAL DEVICE ELECTRONIC MODULE**

(71) Applicant: **DexCom, Inc.**, San Diego, CA (US)

(72) Inventors: **Todd Andrew Newhouse**, San Diego, CA (US); **Ryan Schoonmaker**, Oceanside, CA (US)

(73) Assignee: **DexCom, Inc.**, San Diego, CA (US)

(**) Term: **15 Years**

(21) Appl. No.: **29/785,411**

(22) Filed: **May 25, 2021**

Related U.S. Application Data

(63) Continuation of application No. 29/688,577, filed on Apr. 23, 2019, now abandoned, which is a (Continued)

(57) **CLAIM**

The ornamental design for a medical device electronic module, as shown and described.

DESCRIPTION

FIG. 1 is a top perspective view of an embodiment of a medical device electronic module;

FIG. 2 is a bottom perspective view of the electronic module of FIG. 1;

FIG. 3 is a front view of the electronic module of FIG. 1; FIG. 4 is a rear view of the electronic module of FIG. 1; FIG. 5 is a right side view of the electronic module of FIG. 1;

FIG. 6 is a left side view of the electronic module of FIG. 1;

FIG. 7 is a top view of the electronic module of FIG. 1; and, FIG. 8 is a bottom view of the electronic module of FIG. 1. The broken lines illustrate portions of the medical device electronic module that form no part of the claimed design.

1 Claim, 8 Drawing Sheets

Related U.S. Application Data

continuation of application No. 29/611,636, filed on Jul. 24, 2017, now Pat. No. Des. 851,256, which is a continuation of application No. 29/532,766, filed on Jul. 9, 2015, now Pat. No. Des. 794,201.
